Inventor
MUNSON

F. E. MUNSON
By *Franklin E. Munson* Attorney

UNITED STATES PATENT OFFICE.

FRANK L. MUNSON, OF BERLIN, NEW YORK; FREEMAN H. MUNSON ADMINISTRATOR
OF SAID FRANK L. MUNSON, DECEASED.

TOOL.

Application filed October 26, 1918. Serial No. 259,840.

To all whom it may concern:

Be it known that I, FRANK L. MUNSON, a citizen of the United States, residing at Berlin, in the county of Rensselaer and 5 State of New York, have invented certain new and useful Improvements in Tools; and I do hereby declare the following to be a full, clear, and exact description of the invention, such as will enable others skilled 10 in the art to which it appertains to make and use the same.

My invention relates to improvements in tools, and more particularly to means for fastening the handle of the tool to the shank 15 portion thereof.

A further object of the invention is to provide means of the character described, which are easy to apply, neat in appearance and cheap to manufacture.

20 Other objects and advantages of the invention will be apparent during the course of the following description.

In the accompanying drawings forming a part of this specification, and in which like 25 numerals are employed to designate like parts throughout the same.

Figure 1 is a plan view of my improved fastening device applied to the handle of a screwdriver, and

30 Figure 2 is a side elevation of the same, parts thereof being shown in section.

In the drawings, wherein for the purpose of illustration is shown the preferred embodiment of my invention, the numeral 5 designates a screwdriver, having a reduced shank portion 6. Extended over the shank

35 portion 6 is a handle 7, which may be formed of a pair of scales 7^a disposed in side openings 17 of a frame 17^a.

40 The scales 7 are provided with opposed conical shaped recesses 8, adapted for the reception of conical shaped retaining or wear elements 9. The conical shaped retaining elements 9 are provided with centrally disposed openings 10, adapted for the

45 reception of screws 11. The retaining elements receiving the threaded ends of the screws are interiorly screw-threaded for engagement therewith. These retaining elements are provided with conical shaped re-

cesses 12 in their inner faces to form guides for the ends of the screws 11. It will be apparent that in inserting the screws 11 through the handle and the shank 6 that the contact of the screw with the conical 55 shaped side walls of the recesses will cause the same to be guided into the openings 10. The retaining elements receiving the heads of the screws 11 are provided in their outer faces with conical shaped recesses 13, receiving the heads 14 of the screws 11, and thus permitting of the heads 14 to lie flush with the handle. The portions of the handle 7 surrounding the conical shaped recesses 8 are countersunk for the reception of annular 60 flanges 15, carried by the retaining elements 9.

In applying my improved retaining device to a handle, it will be apparent that the handle is first provided with the conical 70 shaped recesses 8 and the countersunk portions surrounding the conical shaped recesses. The retaining elements 9 are positioned in the conical shaped recesses 8, and the screws 11 engaged therewith.

75 As clearly shown in Figure 2, the screws 11 may be of a greater length than the width of the handle, and are adapted to be severed flush with the outer face of the retaining elements upon their application to a handle.

80 It is understood of course that I may make my improved handle fastener for tools in various sizes and also of any desired material, which in the manufacture of the device I may find the best adapted to the conditions.

85 While I have shown and described the preferred embodiment of my invention, it is understood that I may make such minor changes in arrangement and construction of parts as will remain within the spirit of the invention and the scope of the appended claim.

90 Having thus described my invention, what I claim is:

95 A handle consisting of a frame to receive an attaching shank of a tool, said frame having opposite side openings, scales disposed snugly in said openings enclosed by and in contact with the frame at the mar-

ginal edges of the scales, a screw passing through said scales and shank in order to secure the scale to the shank and thereby prevent longitudinal displacement of the frame, and wear members countersunk into the scales and being relatively large compared with the screw.

In testimony whereof I affix my signature in presence of two witnesses.

FRANK L. MUNSON.

Witnesses:

FREDERICK GOODERMOTE,
ALLEN F. GOODERMOTE.
